RECIPROCATING PUMP

William C. Richardson, Electra, Tex.

Application September 25, 1937, Serial No. 165,750

19 Claims. (Cl. 103—46)

This invention relates to an improvement in reciprocating pumps of the type used for pumping oil or other deep wells in the earth. The invention relates more particularly to the operating mechanism for such pumps.

Heretofore, attempts have been made to operate a deep well pump by fluid pressure, but difficulty has been experienced, first, with the operation of the various valves for controlling the pump, and second, with the deleterious effect of the air or gas that is discharged into the oil being pumped.

The object of this invention is to improve the operating mechanism of a fluid actuated pump of this type, whereby a quick changing of the valves may be obtained automatically and proper and desired operation thereof provided, while at the same time preventing intermixing of the pumping fluid with the oil or other fluid pumped from the well.

In the present invention, the valves are so controlled by a positive quick changing mechanism that no dead center is experienced. The fluid is discharged from the operating mechanism into a separate conduit and conveyed to the surface of the well separate from the pumping oil, whereby there is no intermixing of the pumping fluid with the pumped fluid from the well. Thus the expensive treating that would be necessary to eliminate this pumping fluid from the crude oil intermixed therewith is wholly eliminated.

Although the invention may be embodied in different forms and changes made therein to meet specific needs and requirements, a preferred embodiment of the invention is illustrated in the accompanying drawings in which:

Fig. 1 is a vertical sectional view of a portion of a deep well pump showing the invention applied thereto, parts being in elevation;

Fig. 2 is a side elevation of the latch hook detached;

Fig. 3 is a similar view of a slide standard;

Fig. 4 is a similar view of a slide on the valve trip mechanism;

Fig. 5 is a transverse sectional view through the slide standard, on the line 5—5 of Fig. 3;

Fig. 6 is a similar view through the slide on the line 6—6 of Fig. 4;

Fig. 7 is a vertical sectional view partly in elevation, on an enlarged scale, through the valve chamber;

Fig. 8 is a transverse sectional view therethrough on the line 8—8 of Fig. 7;

Fig. 9 is a similar view on the line 9—9 of Fig. 7;

Fig. 10 is a vertical sectional view through a portion of the pump, partly in elevation, showing the valve trip mechanism;

Fig. 11 is a side elevation of the trip mechanism detached, at a right angle to Fig. 10;

Fig. 12 is a transverse sectional view on the line 12—12 of Fig. 10;

Fig. 13 is a similar view on the line 13—13 of Fig. 10;

Fig. 14 is a vertical sectional view through a portion of the pump showing the stroke linkage chamber, parts being in elevation;

Fig. 15 is a transverse sectional view on the line 15—15 of Fig. 14;

Fig. 16 is a similar view on the line 16—16 of Fig. 18;

Fig. 17 is a vertical sectional view partly in elevation through the power pistons and their cylinders;

Fig. 18 is a similar view through the upper portion of the pump cylinder and travelling valve; and

Fig. 19 is a similar view through the lower portion of the pump cylinder and standing valve.

The form of the invention shown in the drawings is illustrated generally in Fig. 1, and more in detail in the other figures, but Fig. 1 shows the complete pump, but with the pipes connecting the different parts in a diagrammatic illustration, locating these pipes substantially in a single plane, whereas some of these pipes would be out of said plane and slightly offset therefrom.

The pump comprises a casing designated generally by the numeral 22 which is shown as made in sections separated by partitions 23, which divide the casing into power cylinders 24, within which pistons 26 operate. The pistons 26 are attached to a hollow connecting rod 28, slidably mounted in stuffing boxes 29 and 30, in the partitions 23, and the lower end of the piston rod 28 carries a piston 31 and traveling valve 32 operatively mounted in a lower cylinder 33 in the casing. These are shown in details in Fig. 18, from which it will be apparent that the traveling valve is prevented from closing the lower end of the hollow piston rod 28 by a pin 34, so that the fluid may pass the traveling valve and into the lower end of the piston rod.

Figs. 1 and 19 illustrate the usual standing valve designated generally by the numeral 35, which is secured in the lower end of the casing 22, in order to admit fluid into the pump cylinder 33 from which it is forced upwardly through the hollow connecting rod 28.

As shown in Figs. 1, 14 and 15, the upper end of the hollow connecting rod 28 carries a plate 36, through which pass slidable valve control rods 37, each carrying stops 38 and 40 above and below the plate 36, respectively, to engage the said plate 36 upon longitudinal movement of the connecting rod 28, to reciprocate the control rod 37 by lengthwise motion of the connecting rod 28.

As shown in Figs. 10 and 11, the upper end portions of the control rods 37, pass slidably through flanges 42 and 44, and have stops 46 and 48, re-

spectively, above and below the flanges 42 and 44 to engage the latter. The flanges 42 and 44 receive a valve stem 50 which passes therethrough and which has a coiled spring 52 sleeved thereon and bearing at opposite ends on the flanges 42 and 44, normally tending to press said flanges against stops 53 fixed on the valve stem 50.

As shown in Fig. 1, the casing 22 has a partition 54, secured therein provided with an up-standing support 55 having openings 56 therethrough for the passage of fluid from within the support 55 upwardly to the space in the casing above the partition 54.

As shown in Figs. 10 and 11, the support 55 carries an end member 57 to which are secured 15 the lower ends of a pair of standards 58, the upper ends of which standards are secured to an end member 59. The standards 58 are disposed on opposite sides of the valve stem 50 and support the valve casing designated generally by 20 the numeral 60, as shown in detail in Fig. 7.

The valve casing 60 is divided into several valve chambers 61, 62 and 63, and between the chambers 61 and 62 is a fluid chamber 64, while fluid chambers 65 and 66 are provided, respectively, 25 above and below the valve chamber 63. The valve stem 50 carries valves 67, 68, 69 and 70, the valves 67 and 68 being in opposed relation on opposite sides of the chamber 64, while the valves 69 and 70 face and seat in opposite directions 30 alternately in the valve chamber 63.

The valves 68 and 70 are spring-pressed for yieldable movement relative to the valve stem 50, on which the valves 67 and 69 are fixed. A spring 71 in each of the valves 68 and 70 bears at 35 one end against a cup which is pinned to the piston rod at 72, while the opposite end of said spring bears against a gland 73, having packing 74 interposed between the same and the valve, the latter having its movement limited in one 40 direction by a pin 75. This packing prevents any liquid from escaping around the valve stem 50, while the purpose of having one of each pair of valves yieldable is to permit seating thereof and of the other valves on the stem, even though one or more of these should wear more rapidly than the others.

To facilitate assembly, the valve casing 60 is divided into sections separated by packing members 76, having glands 78 to prevent leakage of 50 the fluid from one chamber to an adjoining chamber, while a gland 79 closes the upper end of the valve casing.

For quick changing of the valve mechanism, the means shown in Figs. 1 to 4, 10, 11 and 13 is provided. Each standard 58 is slotted longitudinally and in each slot is mounted a latch 80 pivoted at 81 to the standard 58, intermediate the length thereof, and provided with hooks 82 at the upper and lower ends thereof, respectively, in positions to engage flanges 42 and 44. A latch slide 83 also extends lengthwise of each standard 58, being telescoped thereon and slidable relative thereto. The latch slide 83 has shoulders 84 and 85, adjacent opposite ends thereof on the inner side of the latch slide, while the opposite edge thereof has a closed shoulder 86, at one end and a similar shoulder 87 at the opposite end to contact the curved end portions of the latch 80. An elongated transverse opening 88 is formed in the slide 83 to permit insertion of the pivot pin 81 for assembly of the parts. Each latch slide 83 has a spring catch 89 secured thereto to engage in a notch 90 in the adjacent standard 75

58. This prevents the slides 83 from slipping down until forced by the flange 42.

The power fluid which is pumped down into the well from the surface of the ground is directed 5 through an inlet pipe 91 into the chamber 63 (Fig. 7). Since the valve 70 is open, the fluid will flow into the chamber 64 and into a conduit 92 to the upper ends of power cylinders 24, above the pistons 26. The pressure of this fluid will force the pistons 26 downwardly in their cylinders, while the fluid in the lower ends of the cylinders 24 will be forced thereby into a conduit 93 which extends upwardly therefrom to chamber 61, as indicated by the arrows in Fig. 1. The valve 67 being open, this fluid will be directed into the chamber 64, thence through a conduit 94, back to the surface of the ground at the top of the well.

The downward motion of the pistons 26 will also force the pump piston 31 downwardly in its cylinder 33, causing the liquid trapped in the latter to be forced upwardly through the traveling valve 32 and connecting rod 28, to a point above the power cylinders to where it is discharged in the casing below the partition 54, through which it is forced and around the valve casing 60 out through the top of the pump casing.

When the pistons 26 have approximately reached the limits of their downward movements, the connecting rod 28 will have carried the plate 36 into engagement with the lower stops 48 on the control rods 37, moving said control rods and thereby causing the stops 46 on the upper ends thereof (Fig. 10) to contact flange 42 and compress the spring 52. This will cause the slide 83 to move downward on each standard 58 to a point where the closed side 86 will engage the curved upper end of latch 80, tripping the same and releasing flange 44 for downward movement by the spring 52.

The flange 44 will engage the lower stop 52 on the valve stem 50, thereby causing downward movement of the valve stem to close valves 67 and 70, and opening the valves 68 and 69. This shifting of the valves will cause the motive fluid to be directed from chamber 63 past valve 69 and into a conduit 92, which leads from chamber 65 downwardly to the lower ends of the cylinders 24 to act upwardly on the pistons 26 in their lower positions tending to move them upwardly in the cylinders, and reversing the operation as described above, causing the motive fluid to be forced upwardly from above the pistons into a conduit 93, extending upwardly to chamber 62, past open valve 68 and out through conduit 51 to the top of the well.

On the upstroke of the piston, the valve control rods 37 move stops 48 thereon to push upwardly against the flange 44, and the piston continues to travel upwardly until the slides 83 reach the 60 positions shown in Fig. 10. As soon as the piston reverses, the flange 44 seats upon the jaws of the latch hooks 82, but the outer shoulders 87 of the slides 83 hold the latch hooks engaged with the flange 44. The width of the notches in the latch hooks 82 should be double the thickness of the flanges so the slides will permit the upper flange to be opposite the upper hooks when the lower flange is disengaged by the lower hooks. The shoulders 86 press the upper hooks inward, and on the reverse movement they are pushed outward by the shoulders 84. The shoulders 87 will release the hooks as the slides 83 travel 65 downwardly.

Tight fitting glands 94 are screwed into the casing 22 around the various conduit pipes 88, 89,

90, 91, 92 and 93, to insure tight joints with the casing and to prevent leakage of fluid around these pipes.

I claim:

1. In a deep well pump, the combination of a casing having a plurality of aligned cylinders therein, a pump piston in one of said cylinders, a power piston in an adjacent cylinder, a tubular connecting rod attached to said pump piston mechanically connecting said pump and power pistons together and extending through the power piston for directing pumped fluid therethrough for discharge through the casing, means forming passageways for directing fluid to the power cylinder on respective opposite sides of the power piston, valve means connected with said passageways for controlling the supply of fluid to said power cylinder and having a valve stem connected with the valve means and extending approximately in axial alignment with the connecting rod, and trip means interposed between said valve stem and the connecting rod and connected therewith.

2. In a deep well pump, the combination of a casing having a plurality of aligned cylinders therein, a pump piston in one of said cylinders, a power piston in an adjacent cylinder, a tubular connecting rod extending between the pump and power pistons mechanically connecting said pump and power pistons together and having communication therethrough for forcing fluid from one side of the pump piston to the opposite side of the power piston for discharge through the casing, means forming passageways for directing fluid to the power cylinder on respective opposite sides of the power piston, valve means connected with said passageways for controlling the supply of fluid to said power cylinder and having a valve stem connected with the valve means and extending approximately in axial alignment with the connecting rod, and trip means interposed between said valve stem and the connecting rod and connected therewith.

3. In a deep well pump, the combination of a casing having a plurality of aligned cylinders therein, a pump piston in one of said cylinders, a power piston in an adjacent cylinder, a tubular connecting rod extending through the power piston to the pump piston mechanically connecting said pump and power pistons together and with communication through said pump piston, a valve controlling communication through said pump piston for discharge through the casing, means forming passageways for directing fluid to the power cylinder on respective opposite sides of the power piston, valve means connected with said passageways for controlling the supply of fluid to said power cylinder and having a valve stem connected with the valve means and extending approximately in axial alignment with the connecting rod, and trip means interposed between said valve stem and the connecting rod and connected therewith.

4. In a deep well pump, the combination of a casing having a plurality of aligned cylinders therein, a pump piston in one of said cylinders and having a traveling valve for controlling flow therethrough, a power piston in another of said cylinders, a tubular connecting rod connected with said traveling valve mechanically connecting said pump and power pistons together and extending through the power piston for directing pumped fluid from the pump cylinder through the pump piston and the cylinder thereof for discharge through the casing, means forming

passageways for directing fluid to the power cylinder on respective opposite sides of the power piston, valve means connected with said passageways for controlling the supply of fluid to said power cylinder and having a valve stem connected with the valve means and extending approximately in axial alignment with the connecting rod, and trip means interposed between said valve stem and the connecting rod and connected therewith.

5. In a deep well pump, the combination of a casing having a plurality of aligned cylinders therein, a pump piston in one of said cylinders, a power piston in an adjacent cylinder, a tubular connecting rod extending from the pump piston through the power piston and cylinder thereof mechanically connecting said pump and power pistons together for directing pumped fluid from the pump cylinder upwardly past the power cylinder for discharge through the casing, means forming passageways for directing fluid to the power cylinder on respective opposite sides of the power piston, valve means connected with said passageways for controlling the supply of fluid to said power cylinder and having a valve stem connected with the valve means and extending approximately in axial alignment with the connecting rod, and trip means interposed between said valve stem and the connecting rod and connected therewith.

6. In a reciprocating pump, the combination of a casing having pump and power cylinders therein, pistons in said cylinders, a connecting rod for said pistons, means for supplying fluid pressure to the power cylinder, valves for controlling the inlet and exhaust to said power cylinder, a valve stem therefor, control rods connected with the connecting rod and disposed on opposite sides of the valve stem, spring-pressed means having a lost motion connection between the control rod and valve stem, and trip means normally tending to hold the valve stem in a set position.

7. In a reciprocating pump, the combination of a casing having pump and power cylinders therein, pistons in said cylinders, a connecting rod for said pistons, means for supplying fluid pressure to the power cylinder, valves for controlling the inlet and exhaust to said power cylinder, a valve stem therefor, control rods connected with the connecting rod and disposed on opposite sides of the valve stem, spring-pressed means having a lost motion connection between the control rod and valve stem, trip means normally tending to hold the valve stem in a set position, said trip means including upright standards, a latch pivoted to each standard, and means slidable upon each standard and actuated by movement of the control valves for tripping the latch to cause resilient movement of the valve stem.

8. In a reciprocating pump of the character described, the combination of a casing having pump and power cylinders therein, pistons for said cylinders operatively connected together, means for supplying fluid pressure to said power cylinder, inlet and exhaust valves for controlling said fluid pressure, a valve stem for said valves, and means resiliently connecting one of said valves with the valve stem for yielding action relative thereto.

9. In a reciprocating pump, the combination of a casing having pump and power cylinders, pistons therein operatively connected together, means for supplying fluid pressure to the power

cylinder, a valve casing within the pump casing and spaced from the sides thereof for upward flow therearound, said valve casing having a plurality of chambers therein connected with the fluid supply means, and valve means for controlling communication through said chambers.

10. In a reciprocating pump, the combination of a casing having pump and power cylinders therein, pistons in said cylinders operatively connected together, a valve casing within the pump casing and spaced from the sides thereof for upward flow therearound, said valve casing having a plurality of aligned chambers therein, conduits connecting certain of said chambers with the inlet and exhaust sides of the cylinder, inlet and exhaust conduits connected with other of said chambers, and valve means controlling communication between said chambers.

11. In a reciprocating pump, the combination of a casing having pump and power cylinders, pistons therein, a tubular connecting rod connected with said pistons and extending through the cylinders above the power cylinder for directing fluid upwardly through the casing, a valve casing mounted in the pump casing and spaced from the sides thereof for upward flow therearound, means connecting said valve casing with the power cylinder, and valve means in the valve casing for controlling communication through said connecting means.

12. In a reciprocating pump, the combination of a casing having pump and power cylinders, pistons therein, a tubular connecting rod connected with said pistons and extending through the cylinders above the power cylinder for directing fluid upwardly through the casing, a partition in the casing above the power cylinder having an opening therethrough through which the fluid passes, a valve casing supported by said partition in the casing and spaced from the sides thereof for upward flow of fluid therearound, fluid supply means communicating with the power cylinder and valve casing, and valve means in the valve casing for controlling communication through said supply means.

13. In a reciprocating pump, the combination of a casing having pump and power cylinders, pistons therein, a tubular connecting rod connected with said pistons and extending through the cylinders above the power cylinder for directing fluid upwardly through the casing, a partition in the casing above the power cylinder having an opening therethrough through which the fluid passes, a valve casing supported by said partition in the casing and spaced from the sides thereof for upward flow of fluid therearound, fluid supply means communicating with the power cylinder and valve casing, valve means in the valve casing for controlling communication through said supply means, and lost-motion means interposed between the connecting rod and valve means and connecting the same together.

14. In a reciprocating pump, the combination of a power cylinder, a piston in said cylinder, a piston rod connected with said piston, means for supplying fluid pressure to the power cylinder, valves for controlling the inlet and exhaust to said power cylinder, a valve stem therefor, control rods connected with the connecting rod and disposed on opposite sides of the valve stem,

spring-pressed means having a lost-motion connection between the control rod and valve stem, and trip means normally tending to hold the valve stem in a set position.

15. In a reciprocating pump, the combination of a casing having a power cylinder therein, a piston in said cylinder, a connecting rod for said piston, means for supplying fluid pressure to the cylinder, valves for controlling the inlet and exhaust to said power cylinder, a valve stem therefor, control rods connected with the connecting rod and disposed on opposite sides of the valve stem, spring-pressed means having a lost-motion connection between the control rod and the valve stem, trip means normally tending to hold the valve stem in a set position, said trip means including upright standards, a latch pivoted to each standard, and means slidably upon each standard and actuated by movement of the control valves for tripping the latch to cause resilient movement of the valve stem.

16. In a reciprocating pump of the character described, the combination of a casing having a power cylinder therein, a piston for said cylinder, means for supplying fluid pressure to said power cylinder, inlet and exhaust valves for controlling said fluid pressure, a valve stem for said valves, and means resiliently connecting one of said valves with the valve stem for yielding action relative thereto.

17. Trip mechanism for a valve comprising a pair of upright standards, a latch pivoted to each standard and having hooks at opposite ends thereof, disks in position to engage the hooks, and a latch slide slidably mounted on each standard and having means for tripping the respective latch adapted to cause movement of the valve.

18. In a power device, the combination of a power cylinder, a piston in said cylinder, a piston rod connected with said piston, means for supplying fluid pressure to the power cylinder, valves for controlling the inlet and exhaust to said power cylinder, a valve stem therefor, control rods connected with the connecting rod and disposed on opposite sides of the valve stem, a pair of spring-pressed discs having lost-motion connections with the control rod and valve stem, and trip means normally tending to hold the valve stem in a set position.

19. In a power device, the combination of a casing having a power cylinder therein, a piston in said cylinder, a connecting rod for said piston, means for supplying fluid pressure to the cylinder, valves for controlling the inlet and exhaust to said power cylinder, a valve stem therefor, control rods connected with the connecting rod and disposed on opposite sides of the valve stem, spring-pressed means having a lost-motion connection between the control rod and the valve stem, and trip means normally tending to hold the valve stem in a set position, said trip means including upright standards, a latch pivoted to each standard approximately midway between the ends of said latch, and means slidably upon each standard and actuated by movement of the control valves for tripping the latch to cause resilient movement of the valve stem.
